UNITED STATES PATENT OFFICE

2,522,076

ECCENTRICALLY MOUNTED WHEELED FIGURE TOY

Ferenc Veress, Budapest, Hungary

Application September 13, 1948, Serial No. 49,003
In Hungary August 7, 1947

3 Claims. (Cl. 46—105)

1

The present invention relates to a movable toy figure, especially figure of an animal, which can be pulled or pushed by means of a rod or the like, or it may be driven by a spring controlled device mounted on the toy in such a way that during the movement of the figure the leaping or gallop of the animal is imitated.

The rolling or travelling mechanism of the toy figure according to the invention is formed by an eccentrically mounted wheel or pair of wheels the axle of which is provided on the trunk of the figure or on an elongation of the trunk, and by at least one sliding surface, wheel or roller which is situated on another point of the longitudinal section of the toy and also on the trunk or on the elongation of the trunk, the toy being provided with at least one foot pivoted on the trunk in such a way that during the movement of the toy when the trunk is raised and lowered by the eccentrically mounted wheel or wheels, in consequence of the engagement and disengagement with the floor and of the influence of gravity this foot is turned relatively to the trunk in such a way that the toy figure seems to jump or gallop by means of its feet.

The other particulars of the invention are explained in connection with the embodiments shown in the annexed drawing. In this drawing

Fig. 1 is a side view of the first embodiment given by way of example and showing the figure of an animal;

Fig. 2 is the corresponding plan view and

Fig. 3 shows the function of the toy.

Referring to Figs. 1 and 2, the two eccentrically mounted wheels 3 are fastened on an axle 2 pivoted on an elongation of the trunk of the toy Figure 1. The travelling mechanism of the toy further contains a roller 4 also pivoted on the said elongation of the trunk. Instead of the roller a sliding surface may be employed supporting the toy figure on the floor. On the trunk there are pivotally mounted two pairs of feet 5 and 6.

The feet 5 and 6 are mounted idly in such a way that if the trunk is moved in a vertical plane the feet are turned in respect to the trunk under the influence of gravity. As it is clearly shown in Fig. 1 the feet 5 are pivoted at a place on the trunk which results in a forwardly directed position of these feet. For this purpose it is possible to eccentrically arrange the middle axle of the feet but to employ an eccentrically mounted weight for attaining the said forwardly directed position. The forwardly directed turning motion of the feet is limited by pins 7.

2

Fig. 3 shows the principle of the function of the toy. As illustrated in this figure the most important parts of the trunk 1 are those holding the axle 2, the feet 5 and 6 and the roller 4 or a sliding surface replacing this roller. If the toy figure is not four-footed but two-footed, the parts holding the feet 5 or the feet 6 may be omitted. On the right hand part of Fig. 3 the position of the toy is shown by dotted lines in which it comes after a half rotation of the wheels 3.

The function of the toy is as follows:

In the position shown in Fig. 1 the axle of the wheel 3 is in its lowest position. If now 15 the toy is moved in a forward direction, the roller 4 and the wheels 3 are rolling on the ground. The eccentrically mounted wheels 3 raise the rear part of the trunk 1 by means of the axle 2 and during this movement the feet 6 are turned 20 forwardly under the influence of gravity. Up till now these feet could not take a vertical or approximately vertical position as they engaged the ground. At the same time, as the front part of the trunk 1 is lowered the feet 5 are engaging 25 the ground so that during the forwardly directed movement of the toy the feet 5 remain behind and after a half rotation of the wheels 3 the front feet 5 take their rearmost position and the back feet 6 take their foremost position. This 30 position is shown in Fig. 3 by dotted lines. At the next half rotation of the wheels 3 the rear part of the body 1 is lowered and as the rear feet engage the floor and as the front feet disengage the floor, all the feet take again the 35 initial position.

In this way a motion is produced which is a very good imitation of the gallop of a horse.

Of course the invention is not limited to the 40 illustrated construction forms, but modifications are possible. So for instance one eccentrically mounted wheel 3 may be employed instead of a pair of wheels, but two rollers 4 may be used on a common shaft or axle.

45 I claim:

1. A wheeled figure toy simulating the form of a quadruped capable of galloping movements derived from an eccentric point upon at least one traction wheel, said toy including a quadruped body; four legs pivoted in two front and rear 50 pairs for rocking movement on both sides of the quadruped body; a rigidly depending projection upon the rear portion of the latter body; a front arm extending rigidly forward from the lower portion of the depending projection and terminating beneath the intermediate portion of

said quadruped body; a rotatable support pivoted to the forward end of the front arm for supporting the latter out of direct contact with the ground; a rear arm extending rigidly rearward from the lower portion of said depending projection; a transverse shaft rotatably journaled in the rear end of said rear arm; and a pair of traction wheels eccentrically mounted on said transverse shaft on opposite sides of said rear arm.

2. A wheeled figure toy simulating the form of a quadruped capable of galloping movements derived from an eccentric point upon at least one traction wheel, said toy including a quadruped body; four legs pivoted in two front and rear pairs for rocking movement on both sides of the quadruped body; a rigidly depending projection upon the rear portion of the latter body intermediate the two rear legs; a front arm extending rigidly forward from the lower portion of the depending projection and terminating beneath the intermediate portion of said quadruped body; a rotatable support pivoted to the forward end of the front arm for supporting the latter out of direct contact with the ground; a rear arm extending rigidly rearward substantially in alignment with the front arm from the lower portion of said depending projection beyond the rear end of said quadruped body; a transverse shaft rotatably journaled in the rear end of said rear arm; and a pair of traction wheels eccentrically mounted on said transverse shaft on opposite sides of said rear arm.

3. A wheeled figure toy simulating the form of a quadruped capable of galloping movements

derived from an eccentric point upon at least one traction wheel, said toy including a quadruped body; four legs pendently pivoted in two front and rear pairs for rocking movement on both sides of the quadruped body; a rigidly depending projection upon the rear portion of the latter body intermediate the two rear legs; a front arm extending rigidly forward from the lower portion of the depending projection and terminating beneath the intermediate portion of said quadruped body; a rotatable support pivoted to the forward end of the front arm for supporting the latter out of direct contact with the ground; a rear arm extending rigidly rearward from the lower portion of said depending projection beyond the rear end of said quadruped body; a transverse shaft rotatably journaled in the rear end of said rear arm behind said quadruped body; and a pair of traction wheels having a sufficient diameter to give rise to alternate contact of the front and rear pairs of legs with the ground and eccentrically mounted on said transverse shaft on opposite sides of said rear arm.
